UNITED STATES PATENT OFFICE

121,438

DESIGN FOR A COMBINATION REFRESH- MENT DISH AND TRAY

Alexander Karsh, New York, N. Y.

Application November 16, 1939, Serial No. 88,329

Term of patent 3½ years

To all whom it may concern:

Be it known that I, Alexander Karsh, a citizen of the United States, residing at #255 Haven Avenue, Borough of Manhattan, city, county and State of New York, have invented a new, original and ornamental Design for a Combination Refreshment Dish and Tray, of which the following is a specification, reference being had to the accompanying drawing, forming a part thereof.

In the drawing:

tion refreshment dish and tray, showing my new design.

Figure 2 is a top plan view thereof, on an enlarged scale.

I claim:

The ornamental design for a combination refreshment dish and tray, substantially as shown.

ALEXANDER KARSH.
